Inventor:

Frank M. Sayford,
By his Atty, T. H. Richards.

UNITED STATES PATENT OFFICE.

FRANK M. SAYFORD, OF BROOKLYN, NEW YORK.

COOLING DEVICE.

Application filed November 30, 1921. Serial No. 518,919.

To all whom it may concern:

Be it known that I, FRANK M. SAYFORD, a citizen of the United States, residing in Brooklyn, in the county of Kings and State 5 of New York, have invented certain new and useful Improvements in Cooling Devices, of which the following is a specification.

My present invention relates to cooling devices, and particularly to a cooling device 10 for butter-chips, and one object is to provide a device of this character for use in connection with restaurants and dining rooms.

Another object is to provide a cooling device comprising a cooling portion and a container portion, the container portion being 15 comprised of a plurality of container parts or members and being separable as a whole from the cooling portion for distribution of the material cooled therein, or the parts or 20 members comprising the container portion being separable from each other for convenient distribution of the material appurtenant to such container part or member which has been cooled in the container portion. 25

Another object is to provide a cooling device comprising a cooling portion and a container portion, the container portion being comprised of a plurality of container parts 30 or members and being capable of enlargement by the addition of similar container parts or members.

In the accompanying drawings which show one of the possible embodiments of my 35 invention and which form part of this specification, Figure 1, is a sectional view showing the cooling portion and the container portion overlying the cooling portion and comprised of a plurality of container members or trays.

Figure 2 is a sectional view on the line 2—2 of Fig. 1.

Figure 3, is a perspective view of one of the container members or trays.

Figure 4, is a detail sectional view on an enlarged scale of one of the material holders or butter-chip holders used in association with the container members or trays.

Figure 5, is a fragmentary detail sectional 50 view, on an enlarged scale, of a side and a portion of the bottom or floor of a container member or tray, with a corresponding portion, in outline, of a container member or tray in fitting or conforming engagement with the first container member or tray and in overlying relation thereto.

Similar reference characters are used to denote similar parts throughout the several views.

My invention comprises the cooling portion generally denoted by A, the container portion generally denoted by B, the container members or trays generally denoted by C, and the material holders, or butter-chip holders, generally denoted by D. 60

The cooling portion A preferably is of box form, open at the top, and preferably is made of sheets of metal soldered or otherwise secured together to provide space between the exterior and interior sheets for receiving suitable heat insulating filler, such as charcoal or saw-dust. The container portion A for convenience is not shown in Figs. 1 and 2 of this construction, but preferably is substantially similar in construction to the 70 construction of the trays shown in Fig. 5, and will be readily understood by reference to this figure. The portion A has at the upper edge of its side and end walls an interior rabbet providing the ledge 10 and the 75 upward extension 11.

The cooling portion A is divided into the ice chamber 12 and the fan chamber 13, the fan chamber being open at its top and formed by a rectangular sheet of metal 14 80 flanged or otherwise suitably secured to an interior wall of the cooling portion A and extending from the bottom to within a short distance of the top thereof. The fan chamber 13 has an aperture 15 therein about midway of the height thereof, the purpose of which is later mentioned. The motor driven fan F, the motor of which preferably is electric, is secured in the chamber 13, the fan being above the upper line of the aperture 15. The ice chamber 12 has at one side at the bottom an aperture 16 communicating with the atmosphere, or communicating with means, not shown, for providing pre-cooled air. The coil of piping 17 is arranged in the ice chamber 12, one end of the piping communicating with the aperture 16 and the other end being flanged to the wall 14 and communicating with the aperture 15 before mentioned. 95

Each of the trays C has side and end walls preferably formed of two sheets of metal soldered or otherwise secured together to provide space therebetween for receiving heat insulating filler, Fig. 5, the side and end walls having at the upper interior edge 100 a rabbet providing a ledge 18 and an up- 105

ward extension 19, and having at the lower exterior edge a rabbet providing a bottom-face 20 and a downward extension 21, the intention being that each of the trays C may conformably engage or fit the cooling portion A by engagement of the downward extension 21 with the ledge 10 and engagement of the bottom-face 20 with the upward extension 11 of the cooling portion A, and conformably engage or fit a similar overlying tray C by engagement of the downward extension 21 and bottom-face 20 of the overlying tray with the ledge 18 and upward extension 19 of the underlying tray, the overlying and underlying trays when so engaged forming a box-like container portion.

Each tray C has a floor or bottom 22, preferably formed of a metal sheet flanged or otherwise secured to the interior side of the extension 21 thereof. Each bottom 22 has openings therethrough such as the alined and spaced slits 23 for passage of air, and has apertures therethrough, such as the alined and spaced apertures 24, for receiving the material holders or butter-chip holders D therein. But instead of apertures such as 24 the bottom or floor may be provided with indents, not shown, or other suitable means for retaining the holders D in the trays.

The cover 25 is provided for the container portion, this cover preferably having interior space, not shown, for insulating filler, and having through it apertures such as 26 for passage of air from the container portion. The cover 25 has in its under edge an all around rabbet providing a shoulder 27 and a bottom-face 28, the shoulder 27 being engageable with the ledge 18 and the bottom-face 28 being engageable with the upward extension 19 of a tray C when the cover 25 is in covering position.

The material holders or butter-chip holders D preferably are of the saucer-like form shown in Fig. 5, and may be of paper, wood, metal or any suitable material.

In assembling and operation: The cooling portion A being constructed and arranged as described, ice is placed in the chamber 12 over and around the coil of piping 17. A tray C having thereon material to be cooled, preferably in holders such as D, is arranged in overlying fitting or conforming engagement with the cooling portion A. A second tray C having thereon material to be cooled is arranged in similar overlying engagement with the first tray, and so continued until the desired size of container portion is formed. The cover 25 is arranged in overlying engagement with the uppermost tray, the fan F is started and air admitted to the coil of piping 17 and cooled by the ice in the chamber 12, is forced as a cooling current through the container portion B and over and around the material on the trays C.

For distribution of the cooled material one or more of the trays C may be lifted from engagement with its associated trays and carried to any convenient position; or the whole container portion A with the cooled contents may be moved bodily to a desired position by lifting the lowermost tray, and its associated trays forming the container portion B, from engagement with the cooling portion A.

It will be noted from the foregoing description that the container portion A is extensible or capable of enlargement by the addition of trays C, such extension or enlargement being only limited by the ability of the cooling portion A to cool the contents of the enlarged container portion.

For draining the ice-chamber 12 suitable drainage means, such as the outlet 29, may be arranged in the ice-chamber below the coil of piping 17.

And if desirable a door or doors, not shown, may be provided in the wall of the cooling portion A for access to the ice-chamber 12 and the fan chamber 13.

I thus provide a cooling device which is simple in construction, and convenient in use, and which, due to the separability of its parts, the easy access to its interior and to its being preferably of metal, is easily cleaned and sanitary.

Having thus described my invention it should be understood that there may be modifications thereof and variations therein without departing from the spirit of the invention or exceeding the scope of the appended claims.

What I claim and desire to protect by Letters Patent is:—

1. In a cooling device, the combination with a cooling portion; of a container portion separably superimposed on the cooling portion; the container portion being composed of a plurality of separably connected containers superimposed on each other, each of which has side walls, end walls and a bottom; said side and end walls of the superimposed containers providing the outer side and end walls of the container portion and when the container portion is superimposed on the cooling portion being alined with the outer side walls and end walls of the cooling portion, passages in said container portion, and means in said cooling portion for circulating cooled air through said passages.

2. In a cooling device, the combination with a cooling portion; of a container portion interlockably superimposed on the cooling portion; the container portion being composed of a plurality of interlockably connected containers superimposed on each other, each of which has side walls, end walls and a bottom; said side and end walls of the superimposed containers providing

the outer side and end walls of the container portion and when the container portion is superimposed on the cooling portion being alined with the outer side walls and 5 end walls of the cooling portion, passages in the bottoms of said containers, and means in said cooling portion for circulating cooled air through said passages.

3. In a cooling device, the combination 10 with a cooling chamber, a container portion consisting of a plurality of superimposed interlocking containers, air passages in the bottoms of said containers, depressions in the bottoms of said containers for 15 the reception of the material to be cooled, a removable cover for the uppermost container having air vents therein, and means for drawing air into the cooling chamber, said means subsequently serving to distribute 20 the air drawn into the cooling chamber, through the passages in the containers, whereby to cool the products located therein.

4. In a cooling device, the combination 25 of, a cooling portion; a container portion separably superimposed on the cooling portion; the container portion being composed of a plurality of separably connected containers superimposed on each other, each of 30 which has side walls, end walls and a bottom having air passages therethrough; said side and end walls of the superimposed containers providing the outer side and end walls of the container portion and when the 35 container portion is superimposed on the cooling portion being alined with the outer side and end walls of the cooling portion; a removable cover for the uppermost of the superimposed containers having air 40 vents therein; a cold air chamber in the cooling portion; means for passage of cold air from said chamber to the air passages of the lowermost of the superimposed containers; and means for forcing cold air 45 through said air passages.

5. In a cooling device, the combination 50 of, a cooling portion; a container portion interlockably superimposed on the cooling portion; the container portion being composed of a plurality of interlockably connected containers superimposed on each other, each of which has side walls, end walls and a bottom having air passages therethrough; said side and end walls of 55 the superimposed containers providing the outer side and end walls of the container portion and when the container portion is superimposed on the cooling portion being alined with the outer side and end walls 60 of the cooling portion; a removable cover for the uppermost of the superimposed containers having air vents therein; a cold air chamber in the cooling portion; means for passage of cold air from said chamber to the air passages of the lowermost of the 65

superimposed containers; a second chamber in the cooling portion communicating with said means for passage of cold air; a fan in the last mentioned chamber; and means for driving said fan.

6. In a cooling device, the combination 70 of, a cooling portion; a container portion; the container portion being composed of a plurality of interlockably connected containers superimposed on each other, each 75 of which has side walls, end walls and a bottom having air passages therethrough and depressions in its upper surface; said side and end walls of the superimposed containers providing the outer side and end walls of the container portion, the container portion being superimposed on the cooling portion by interlocking engagement of the lowermost of the superimposed containers 80 with the cooling portion, and said side and end walls then being alined with the outer side and end walls of the cooling portion; a removable cover for the uppermost of the superimposed containers having air vents 85 therein; a cold air chamber in the cooling portion; means for passage of cold air from said chamber to the air passages of the lowermost of the superimposed containers, a second chamber in the cooling portion 90 communicating with said means for passage of cold air; a fan in the last mentioned chamber; and a motor for driving said fan.

7. In a cooling device, the combination 95 with a cooling portion, and a container portion, said container portion being formed by a plurality of container sections in superimposed interlocked relation, of air passages in the bottoms of said container, depressions along the bottoms of the containers for locating the material to be cooled therein, and means in said cooling chamber for distributing a current of cooled air through the passages in the containers, whereby to cool the material located therein.

8. In a cooling device, the combination 100 with a cooling portion, and a container portion, said container portion being formed by a plurality of container sections in superimposed interlocked relation, of air passages 105 along the bottoms of said container sections depressions along the bottom of the container portion for positioning the material to be cooled thereon, an air feed passage in the cooling portion, means in said cooling portion for cooling the passage and means for distributing the pre-cooled air through the air passages in the container portion.

9. In a cooling device, the combination 115 of, a cooling portion; a container portion; means appurtenant to the cooling portion for forcing a current of air from the cooling portion through the container portion; the container portion being formed by a plurality of container members similar to 120

each other, arranged in overlying and underlying relation to each other, and having bottoms perforated for passage of air therethrough; said members being conformably engageable with each other at the points of contact between the members when in overlying and underlying relation; the undermost of said members, when said members are in overlying and underlying relation, being engageable with the cooling portion for operatively connecting the container portion thereto; and said cover being perforated for passage of air therethrough and engageable with the uppermost of said members when said members are in overlying and underlying relation.

10. In a cooling device, the combination

with a cooling chamber, of means for cooling incoming air in said cooling chamber, a container portion consisting of a plurality of container sections superimposed above one another in interlocking relation, positioned above and adjoining the cooling chamber, passages in the bottoms of said container sections and means cooperating with the air cooling means for distributing the cooled air through the passages in the container sections whereby to cool the materials contained therein.
